LENS HOUSING FOR AUTOMOBILES

Karl Wilfert, Stuttgart-Degerloch, Germany, assignor to
Daimler-Benz Aktiengesellschaft, Stuttgart-Untertuerk-
heim, Germany

Application May 4, 1956, Serial No. 41,356

Term of patent 7 years

(Cl. D48—32)

FIG.1

FIG.2

FIG.3

FIG.4

Figure 1 is a front view of a lens housing for automobiles embodying my new design.

Figure 2 is a side view on an enlarged scale of the housing shown in Figure 1.

Figure 3 is a front view of the housing shown in Figure 2, and

Figure 4 is a cross sectional view taken along line 4—4 of Figure 1.

The fragmentary portions of an automobile shown in broken lines are for purposes of illustration only.

I claim:

The ornamental design for a lens housing for automobiles, substantially as shown and described.
